MAILBOX

Henry C. Keeler, Sherman Oaks, Calif.

Application August 29, 1949, Serial No. 4,754

Term of patent 14 years

(Cl. D74—9)

To all whom it may concern:

Be it known that I, Henry C. Keeler, a citizen of the United States, residing at Sherman Oaks, in the county of Los Angeles and State of California, have invented a new, original, and ornamental Design for a Mailbox, of which the following is a specification, reference being had to the accompanying drawing, forming part thereof.

Fig. 1 is a front perspective view of a mailbox, showing my new design.

Fig. 2 is a rear elevational view thereof.

Fig. 3 is a side elevational view thereof taken from the right of Fig. 2.

I claim:

The ornamental design for a mailbox, substantially as shown.

HENRY C. KEELER.
